UNITED STATES PATENT OFFICE.

ADOLPH G. KANTMANN, OF OWENSBORO, KENTUCKY, ASSIGNOR TO ANGLO-AMERICAN MILL COMPANY, OF OWENSBORO, KENTUCKY, A CORPORATION OF KENTUCKY.

FEED MIXER.

Application filed June 23, 1928. Serial No. 287,848.

The present invention relates to improvements in feed mixers, and particularly to mixers designed for the purpose of preparing sweetened stock feed.

5 In recent years, considerable attention has been paid to the manufacture of sweetened feed for stock, particularly dairy cattle. Such feed consists commonly of a mixture of grain and a sweetened liquid, molasses having been generally employed.

The advantages of a feed of this nature are appreciated by stock men and various forms of mixing apparatus have been invented for producing a thorough mixture.

15 Commonly, the molasses or liquid content of the feed has been heated before it is mixed with the grain, such heating being designed to thin the normally relatively heavy liquid to permit it to be effectively mixed 20 with the grain.

However, considerable difficulty has been experienced in maintaining the molasses, for example, at the desired temperature, it having been found that the molasses is frequently heated to such a degree that fermentation occurs, thus rendering the product unpalatable to stock and also the product of the methods and apparatus heretofore commonly employed has frequently been 30 unduly moist, so that it easily "balls" or forms relative large cakes or masses which are not suitable for feeding purposes.

The object of the present invention is to provide a mixing apparatus in which the grain and molasses, or other sweetened liquid, are supplied to the mixing receptacle at normal atmospheric temperatures. Further, the apparatus of the present invention supplies the molasses to the mixing receptacle in a solid stream or body as distinguished from spraying or dispersing the particles thereof as they are introduced into the receptacle.

The improved apparatus includes means 45 for thoroughly mixing and agitating the ingredients and means cooperating with such agitating devices for producing the necessary heat to effect a very thorough and intimate mixture between the grain and molasses.

In the accompanying drawing,

Figure 1 is an elevation, partly broken away of an apparatus constructed in accordance with the present invention.

Figure 2 is a transverse section substantially on the line 2—2 of Figure 1, on an enlarged scale.

Figure 3 is a view of a modification.

Referring to the drawing in the several views of which like characters designate corresponding parts, 1 designates the body of the mixing receptacle. This, as shown, more or less conventionally, is preferably of cylindrical form in transverse cross-section and relatively elongated. Adjacent one end, 65 the receptacle is provided with a grain inlet communicating with a conduit or grain supply duct 2, and near its opposite end the receptacle has an outlet communicating with a delivery duct 3. The molasses is supplied 70 to the interior of the receptacle through a feed pipe 4, which is connected with suitable means for supplying the molasses at normal temperature under pressure, so that it will flow over the inwardly projecting 75 end of the feed pipe in a solid stream.

Interiorly of the receptacle 1, is arranged an agitating means comprising a shaft 5 mounted in bearings at opposite ends of the receptacle and provided with a series of 80 suitable agitating arms or stirring blades 6. The blades or arms 6 are arranged relatively to the shaft in a substantially spiral manner, so that as the shaft is rotated, the material treated will be moved longitudinally 85 through the mixer from the inlet to the outlet thereof. The length of each of the agitating arms is such that the outer ends thereof are always spaced a reasonable distance from the wall of the receptacle. The distance separating the ends of the agitating arms of the receptacle will, of course, vary 90 according to the diameter of the receptacle, but it has been found that in an apparatus in which the mixing receptacle is approximately 95 seventeen inches in diameter, that there should be a clearance of approximately two inches between the wall thereof and the ends of the agitating arms.

The power for rotating the shaft and arms 100 thereon is supplied from any suitable motor (not shown) and the agitation of the material is particularly of the form of a centrifugal agitation tending to create a vortex along the axis of the shaft and to maintain the 105 grain content in a constant state of agitation and suspension.

The molasses is delivered from the pipe 4

into the receptacle 1 in a solid unbroken column, and at normal temperatures without being preliminarily heated. The pressure means employed for feeding the molasses through the pipe 4 is sufficient merely to deliver the molasses in a steady stream, and the pipe is of relatively large size, so that without undue pressure the molasses may be fed through it even at low temperatures. 5 Very satisfactory results are obtained and a superior product produced when the molasses is supplied to the receptacle at a temperature of approximately 60°.

As the unbroken column of molasses 15 passes from the feed pipe 4, it is at once subjected to the action of the agitating means within the receptacle and incidentally broken up and dispersed through the agitating area where it combines, while in suspension, with the suspended particles of feed, 20 producing a thorough and uniform mixture. The stirring or agitating arms are so related to the shaft that they act to effect a gradual movement of the mixture toward the receptacle outlet, and to insure a very intimate 25 mixing of the molasses and grain, means are provided for generating in connection with said stirring arms a certain degree of heat which acts to insure that all of the particles 30 of grain will be properly treated and coated with the molasses.

One means for providing such a heating step includes rings 10, 11, which are secured to the inner face of the wall of the receptacle 1, and the vertical faces of which act to retard somewhat the movement of the mixture toward the outlet 3.

In the embodiment of the invention illustrated, only two of these rings are provided, 40 but it will be understood that the number of such rings may be varied according to circumstances, size of apparatus, etc. The rings are located between the molasses feed pipe and the outlet 3, and as shown each is of 45 angle form in cross-section, the annular flanges being bolted, riveted or otherwise secured to the walls of the mixing receptacle.

The frictional heat developed by the contact of the mixture with said retarding rings 50 and the stirring arms or blades will uniformly heat both the grain and molasses, so that the effect is quite different and practically superior to methods and apparatus in which the molasses is preliminarily heated 55 above the temperature of the grain. The uniformly heated and thoroughly mixed grain and molasses is discharged through the outlet 3 in the form of a product which is light, and relatively dry.

60 Instead of producing the frictional heat referred to by contact of the mixture with a retarding ring or rings, it is possible that this action can be obtained by arranging the stirring arms or agitators in different relations to the shaft at various points in the

length of the latter. If, for example, the agitating fingers 6^a adjacent the planes of the grain inlet and molasses feed pipe, are set at an angle of approximately 30° to the axis of the shaft, and the remaining agitating arms 6^b are positioned to extend at an angle of substantially 90° to the shaft, the latter arms will act as a retarding means and thus create the necessary friction within the mass to heat the same as described. 70 75

I claim:

1. In a feed mixer, the combination of a closed receptacle having inlets for feed and molasses, respectively, and an outlet, means in the receptacle to agitate the feed and commingle the particles thereof with the molasses while feeding the mixture toward the outlet, and means attached to the receptacle for retarding movement of the mixture toward the outlet and cooperating with the agitating means to create frictional heat to assist in mixing the feed and molasses. 80 85

2. In a feed mixer, the combination of a closed receptacle having inlets for feed and molasses, respectively, and an outlet, a rotary shaft within the receptacle provided with stirring arms for agitating the feed and commingling the particles thereof with the molasses while feeding the mixture toward the outlet, and rings secured to the receptacle 90 and extending radially inwardly from the walls thereof to retard movement of the mixture toward the outlet and by contact with the mixture generate heat to assist the mixing operation. 95

3. In a feed mixer, the combination of a closed receptacle having an inlet for feed adjacent one end, an outlet adjacent the opposite end and an inlet for molasses between the feed inlet and outlet, rotary stirring means in the receptacle to agitate the feed and commingle the particles thereof with the molasses while feeding the mixture to the outlet, and rings secured to the receptacle between the molasses inlet and the outlet for retarding the movement of the mixture and by friction with the mixture generating heat to assist the mixing. 100 105 110

4. In a feed mixer, the combination of a closed receptacle having an inlet for molasses in its bottom, an independent inlet for feed and a mixture outlet, of a rotary stirrer within the receptacle adapted to agitate the feed therein and commingle the particles thereof with molasses while feeding the mixture toward the outlet, and a ring, of angle form in cross section, surrounding the axis of the stirrer and connected to the receptacle, one member of said ring acting to retard movement of the mixture toward the outlet and to cooperate with the stirrer in generating frictional heat to assist in the mixing. 115 120 125

In testimony whereof I have hereunto set my hand.

ADOLPH G. KANTMANN.
